(57) CLAIM

The ornamental design for a medicine ball, as shown and described.

DESCRIPTION

FIG. 1 is a perspective view of a medicine ball, showing our new design;

FIG. 2 is a front elevation view thereof;

FIG. 3 is a right elevation view thereof;

FIG. 4 is a rear elevation view thereof;

FIG. 5 is a left elevation view thereof;

FIG. 6 is a bottom view thereof; and,

FIG. 7 is a top plan view thereof.

The broken lines shown in the drawings illustrate environment and form no part of the claimed design.
